US0D1068716S

(12) **United States Design Patent** (10) Patent No.: **US D1,068,716 S**
(45) Date of Patent: ** Apr. 1, 2025

(54) **IN-VEHICLE AMPLIFIER**

(71) Applicant: **ALPS ALPINE CO., LTD.**, Tokyo (JP)

(72) Inventors: **Masatada Muramoto**, Tokyo (JP);
Hideki Endo, Tokyo (JP)

(73) Assignee: **ALPS ALPINE CO., LTD.**, Tokyo (JP)

(**) Term: **15 Years**

(21) Appl. No.: **29/844,474**

(22) Filed: **Jun. 29, 2022**

(30) **Foreign Application Priority Data**

Feb. 2, 2022 (JP) ..... 2022-002011 D

(57) **CLAIM**

The ornamental design for an in-vehicle amplifier as shown and described.

DESCRIPTION

FIG. 1 is a perspective view from the front and bottom of an in-vehicle amplifier showing the new design;

FIG. 2 is a perspective view from the front and top thereof;

FIG. 3 is a front view thereof;

FIG. 4 is a rear view thereof;

FIG. 5 is a top view thereof;

FIG. 6 is a bottom view thereof;

FIG. 7 is a right side view thereof;

FIG. 8 is a left side view thereof; and,

FIG. 9 is an alternate front and bottom perspective view thereof, showing transparent material covering the two rectangular areas seen on the top, center surface of the article. The broken lines shown are included for the purpose of illustrating portions of the in-vehicle amplifier that form no part of the claimed design.

1 Claim, 9 Drawing Sheets
